UNITED STATES PATENT OFFICE.

WILLIAM WILSON, OF BOSTON, MASSACHUSETTS, ASSIGNOR TO CAMPBELL BOSWORTH MACHINERY COMPANY, OF PORTLAND, MAINE, A CORPORATION OF MAINE.

LOOP-SEWING ATTACHMENT FOR SEWING-MACHINES.

1,241,182.

Specification of Letters Patent. Patented Sept. 25, 1917.

Application filed April 16, 1915. Serial No. 21,775.

To all whom it may concern:

Be it known that I, WILLIAM WILSON, a citizen of the United States, residing at Boston, in the county of Suffolk and State 5 of Massachusetts, have invented certain new and useful Improvements in Loop-Sewing Attachments for Sewing-Machines; and I do hereby declare the following to be a full, clear, and exact description of the invention, 10 such as will enable others skilled in the art to which it appertains to make and use the same.

The present invention relates to an improvement in loop-sewing attachments for 15 sewing machines. The object of the invention is to reorganize and simplify the construction of loop-sewing attachments whereby the operation of sewing harness or other loops may be more expeditiously performed. To 20 this end the invention consists in the loop-holder hereinafter described and particularly pointed out in the claims.

In the accompanying drawings illustrating the preferred form of the invention, 25 Figure 1 is a side elevation of a part of a sewing machine showing the application of the improved loop-holder thereto; Fig. 2 is a partial sectional elevation of the parts shown in Fig. 1; Fig. 3 is a plan of the improved loop-holder shown in Fig. 1; Figs. 4 and 5 are sectional views of a modified form of loop-holder; and Figs. 6 and 7 are perspective views of harness loops formed on the improved loop-holder.

30 The sewing machine of the illustrated embodiment of the invention may be of any usual or preferred form, that shown being the well known Campbell wax thread machine, the parts of the sewing machine necessary to disclose the application of the improved loop-holder thereto comprising a shuttle-race 10, a presser foot 11 and a needle 13. The improved loop-holder, which is indicated generally by the reference character 35 15, performs the function of presenting the harness loop to be sewn, at the correct angle to the needle so that as the needle rises during the operation of sewing a seam it may clear the under side of the loop and 40 penetrate the margin of the upper side of the loop so as to form a seam therein parallel to the edge of the loop. The loop-holder 15 comprises a work table or body portion 16 and a support therefor consisting 45 of an upright 18 and a base 19. Upon the 50 work table rests the work or loop 17, upon which the seam sewing operation is to be performed. The body or work table 16 in the form of the invention shown in Figs. 1, 55 2 and 3 is made integral with the upright 60 18 and projects perpendicularly therefrom. The upright 18 is integral with the base 19, the angular relation between the upright 18 and the base 19 being the angle of presentation of the work to the needle during the 65 formation of the seam. The loop-holder is mounted upon the shuttle-race 10, the base 19 of the holder being provided with a groove 20 in which is received a spline 21 projecting upwardly from the shuttle-race 70 10, the arrangement being such that the loop-holder is held against lateral movement. Provision for longitudinal adjustment of the loop-holder is secured by means of a slide 23 movable longitudinally in the shuttle-race 75 10 and a screw 24 having a flange 25, the rim of which is received in a slot in the slide 23. The loop-holder is secured in adjusted position by means of the screw 26 which clamps the slide 23 and the base 19 of the loop- 80 holder rigidly to the shuttle-race 10.

The width of the margin formed between the seam and the edge of the loop may be regulated by means of an edge gage 28 which consists of a gage plate 29 and a top plate 85 30 arranged at right angles to each other. The gage plate 29 is provided with a hole of such size and formation that it fits loosely around the body of the work table 16. The edge gage 28 is secured to the upright 18 90 by means of screws 32 which pass through the elongated holes 33 formed in the top plate and are received in threaded holes in the upright. The elongated holes 33 provide for the lateral adjustment of the edge 95 gage, the screws 32 securing the edge gage in adjusted position. The upper portion of the body or work table 16 is made flat so that the loop may rest thereon in the correct position for the sewing operation; a 100 slot 35 passing angularly through the work table being provided for the needle. The above-described construction and arrangement of parts is such that when the strip of leather, with its properly scarfed ends, of 105 which the loop is to be formed, rests upon the work table, the needle, as it rises during the sewing operation, clears the lower side of the loop and passes through the margin of the upper side of the loop so as to form 110

a seam therein arranged angularly to the face of the loop and parallelly to the edge thereof. When the seam on one margin of the loop is formed, the loop is removed from the work table and the other margin presented to the needle. If it is necessary at any time to remove the loop-holder from the machine, this may be done by simply taking out the screw 26 and lifting off the loop-holder, which may again be restored to its operative position, without adjustment of parts, by simply replacing the loop-holder and securing it to the shuttle race by the screw 26. It is obvious, therefore, that the improved loop-holder is one of great simplicity of construction and of certainty of operation; the edge gage 28 affording means whereby the width of the margin formed between the seam and the edge may be regulated.

In the modified form of the invention shown in Figs. 4 and 5 the body or work table 40 is provided with a shank 41 which is received in a hole in the upright 42 and is secured therein by means of the set screw 43. In other respects the work table 40 is substantially the same as the form shown in Figs. 1, 2 and 3. The construction of the modified form of loop-holder is such that it may be easily removed and work tables of different size and form inserted. It will be readily perceived that both forms may be used for sewing loops of various sizes and shapes such as are shown in Figs. 6 and 7.

The present invention contemplates a loop-sewing attachment for sewing machines of such form and construction that the work resting thereon is always presented at the correct angle for the seam sewing operation, the necessity for either angular or lateral adjustment being eliminated; means being also provided for regulating the width of the margin formed by the seam. The invention may, therefore, be embodied in other forms than that shown in the illustration thereof.

Having thus described my invention, what I claim is:

1. A loop-sewing attachment for sewing machines having, in combination, a shuttle-race, and a loop-holder mounted thereon comprising a work table tipped obliquely with relation to the path of the needle so that the part of the loop resting on the work table may be pierced by the needle while the under part of the loop is cleared thereby, means secured to the shuttle-race for supporting the work table in its oblique position, and means surrounding the work table and against which one end of the loop is

adapted to abut, for preventing the under part of the loop from interfering with the needle and for determining the width of the margin formed between the seam and the edge of the loop.

65

2. A loop-sewing attachment for sewing machines having, in combination, a shuttle-race and a loop-holder mounted thereon, comprising a base, an upright, a work table for presenting loops to the needle, and an edge gage movable longitudinally of the work table for regulating the width of the margin formed between the seam and the edge of the loop.

70

3. A loop-sewing attachment for sewing machines having, in combination, a shuttle-race, and a loop-holder mounted thereon comprising a work table tipped obliquely with relation to the path of the needle so that the part of the loop resting on the work table may be pierced by the needle while the under part of the loop is cleared thereby, an upright to which the work table is secured, and a base adapted to be fastened to the shuttle-race, for supporting the upright, said upright and said base having an angular relation equal to the angle between the work table and the path of the needle.

75

4. A loop-sewing attachment for sewing machines having, in combination, a shuttle-race and a loop-holder mounted on the shuttle-race, having provision for longitudinal adjustment thereon.

80

5. A loop-sewing attachment for sewing machines having, in combination, a work table, a support therefor for presenting the loop at the proper angle to the needle and an edge gage having provision for movement longitudinally of the work table for regulating the width of the margin formed between the seam and the edge of the loop.

85

6. A loop-sewing attachment for sewing machines having, in combination, a shuttle-race, a work table, a support for the work table mounted on the shuttle-race, the work table and support being constructed and arranged for presenting the loop at the proper angle to the needle, and an edge gage for regulating the width of the margin formed between the seam and the edge of the loop consisting of a gage plate and a top plate arranged at right angles to each other, the gage plate having provision for engaging the top and bottom sides of the loop and the top plate having provision for lateral movement relatively to the work table support thereby permitting the gage plate to move longitudinally of the work table.
